UNITED STATES PATENT OFFICE.

RALPH W. ERSKINE, OF MISHAWAKA, INDIANA, ASSIGNOR TO WESTINGHOUSE ELECTRIC & MANUFACTURING COMPANY, A CORPORATION OF PENNSYLVANIA.

DESIGN FOR A LIGHTING STANDARD.

Application filed May 27, 1929. Serial No. 31,419. Term of patent 7 years.

To all whom it may concern:

Be it known that I, RALPH W. ERSKINE, a citizen of the United States, residing at Mishawaka, in the county of St. Joseph and State of Indiana, have invented a new, original, and ornamental Design for Lighting Standards, of which the following is a specification, reference being had to the accompanying drawing, constituting a part hereof.

The figure is an elevational view of a light-

ing standard showing my new design with a portion of the standard broken away to permit showing of the remaining portion in greater detail.

I claim:

The ornamental design for a lighting standard substantially as shown.

In testimony whereof, I have hereunto subscribed my name this 11 day of May, 1929.

RALPH W. ERSKINE.
